TENSION CONTROL SYSTEM

Arthur W. Sear, Stratford, Conn., assignor to
General Electric Company, a corporation of
New York

Application October 30, 1945, Serial No. 625,504

17 Claims. (Cl. 242—54)

1

My invention relates generally to tension control systems for traveling strip material such as wire, tape, and the like. More particularly, the invention relates to wire driving and reeling mechanisms for magnetic wire recording apparatus and the like, and has for its object the provision of an improved system and apparatus for maintaining substantially constant wire speed and tension.

The recording medium commonly used in magnetic wire recording apparatus is a slender wire of suitable magnetizable material approximately 4 mils in diameter. This fragile wire is generally drawn through the recording unit at speeds up to approximately 6 feet per second. It will therefore be evident that, in order to prevent breakage of the wire, it is necessary accurately to control its tension. In some recording units now in use the take-up spool is driven at approximately a uniform speed so that, as the wire builds up on the take-up spool, the linear speed of the wire through the recording head increases. This slow variation in speed does not ordinarily affect the fidelity of reproduction, since the wire is usually run through the apparatus in the same direction in reproducing operation as in recording operation. If, however, the wire is cut, so that a portion of the wire upon which a recording was made at one limit of winding of the take-up spool is played back with the take-up spool near its opposite limit of winding, the difference between recording and reproducing speeds will have an undesirable effect upon the reproduction.

A more pronounced disadvantage of the take-up reel drive is that, as the wire builds up, its surface becomes somewhat uneven. The uneven surface causes irregular motion of the wire which results in sudden speed changes or "wow" in reproduction. It will therefore be evident that, for fidelity of reproduction, it is desirable to run the wire at a predetermined fixed linear speed at all times. Moreover to prevent breakage of the wire, and to prevent wire slippage where a capstan drive is used, it is desirable that the tension be maintained substantially constant.

Accordingly, it is a general object of my invention to provide an improved tension control system for strip material winding and reeling apparatus.

Still another object of my invention is the provision of constant tension driving means for a reversible strip winding apparatus or the like.

It is a further object of my invention to provide constant linear speed driving means for strip material winding and reeling apparatus.

It is a more particular object of the invention to provide an improved wire driving apparatus for magnetic wire recording equipment and the like.

2

It is a still further object of my invention to minimize "wow" in magnetic recording and reproducing apparatus and the like.

It is a specific object of my invention to provide a readily reversible constant speed and constant tension wire driving apparatus for magnetic wire recording equipment and the like.

In accordance with a preferred embodiment of my invention, a constant speed driving pulley or capstan intermediate the supply and take-up reels is arranged to drive the wire at a substantially constant linear speed independent of the reel speeds. The reels themselves are both driven in the direction of travel of the wire through separate variable transmission elements from a common friction driving disk. The reel speeds are controlled to maintain the wire tension substantially constant by providing between the capstan and each reel a dancer pulley arranged to control the driving ratio of the transmission element associated with the adjacent reel. Each variable transmission comprises a friction spool connected to transmit power from a driving disk to a driven disk. The spool is mounted upon a linkage permitting axial movement of the spool to control the speed ratio between the disks; and the linkage is so arranged that a damping function is introduced into the motion of the spool, thereby to minimize hunting of the apparatus.

My invention itself, along with further objects and advantages thereof, will be fully appreciated by referring now to the following detailed specification taken in conjunction with the accompanying drawings, in which Fig. 1 is an exploded perspective view of a magnetic recording apparatus embodying my invention; Fig. 2 is a plan view of the front panel of the apparatus shown at Fig. 1; Fig. 3 is a schematic line diagram showing the transmission linkage of Fig. 1 in elevation; Fig. 4 is a vector diagram of velocity illustrating the theory of operation of a single friction transmission element; Fig. 5 is a schematic diagram of a single transmission element embodying my invention in another form; and Fig. 6 is a front elevation of still another transmission linkage embodying my invention.

At Fig. 2 I have indicated schematically the layout of the front panel of a magnetic recording apparatus embodying my invention. As indicated in this figure, a traveling magnetic recording medium, such as a wire 1, is passed between a pair of spaced reels 2 and 3 through a magnetic recording head 4 and an erasing head 5. In passing between the reels, the wire 1 passes over a driven capstan 6 intermediate the reels, a pair of dancer pulleys 7 and 8 on opposite sides of the capstan, and a pair of level winding idler pulleys 9 and 10 intermediate the danc-

er pulleys 7 and 8 and the reels 2 and 3, respectively. I have also shown mounted upon the panel a control switch 11 and a reversing lever 12.

Referring now to Fig. 1, I have shown therein a perspective view of the apparatus with the panel removed. Driving power is obtained from a reversible electric motor 13 controlled by the line switch 11 and a reversing switch 14. The switch 14 connected by a suitable linkage 15 to a reversing shaft 12a connected to the reversing lever 12. A friction roller 16 mounted upon the shaft of the motor 13 drives a disk 17 mounted upon a shaft 18. The disk 17 is preferably of appreciable mass, so that by its flywheel effect it aids in stabilizing the wire speed. The wire driving capstan 6 is mounted upon the opposite end of the shaft 18.

The motor 13 also drives both reels 2 and 3 in the direction in which the wire is traveling and at such speeds that the wire tension forces adjacent each reel are maintained substantially constant and equal. For this purpose, the shaft 18 is provided with a pulley 19 connected through a belt 20 to drive a pulley 21 mounted upon a shaft 22 parallel to the shaft 18. The shaft 22 carries a friction driving disk 23. The disk 23 is connected by separately variable friction transmission mechanisms 24 and 25 to drive a pair of driven friction disks 26 and 27, respectively. The disks 26 and 27 are disposed in the same plane as the disk 23 and are mounted upon shafts 28 and 29, respectively. The shafts 28 and 29 are parallel to the shaft 18 and carry at their opposite ends the reels 2 and 3, respectively.

The transmission elements 24 and 25 are of similar construction and each comprises a pair of parallel jackshafts 30, 31 mounted in quills 32 and 33, respectively, and carrying at opposite ends friction rollers engaging the disk 23 and one of the disks 26 or 27. Referring specifically to the transmission element 25, the jackshaft 30 carries at opposite ends a pair of friction rollers 34 and 35, while the jackshaft 31 carries a similar pair of friction rollers 36 and 37. The rollers 34 and 35 on the shaft 30 are in lateral alignment with the rollers 36 and 37, respectively, on the shaft 31. The rollers 34 and 36 engage the driving disk 23 and the rollers 35 and 37 engage the driven disk 27. The quills 32 and 33 are connected together by a plate 38 fixedly connected to the quill 33 and having a pin and slot connection with the quill 32. The quills 32 and 33 are positioned on opposite sides of the disks 23 and 27 and are biased toward each other to bring the rollers into engagement with opposite sides of the disks. Biasing of the quills is accomplished by means of a tension spring 39 connected between the quills.

The transmission mechanism 25 is mounted upon a pair of links 40 and 41, the upper ends of which are pivotally connected to opposite ends of the quill 32. Similarly, the transmission mechanism 24 is mounted upon a pair of links 42 and 43. The lower ends of the links 40 and 42, which will be referred to hereinafter as control links, are pivotally connected to rocker arms 44 and 45, respectively. The rocker arms 44, 45 are mounted upon fixed pivot pins 46 and 47, respectively. The lower ends of the links 41 and 43, which will be referred to hereinafter as damping links, are connected to pins 48 and 49, respectively, which are slidably mounted in arcuate slots 50 and 51, respectively, in a fixed panel 52. The pins 48 and 49 are connected together by a shift 75

bar 53, and the pin 48 is provided with an extension 54 engaging a slot in one end of a rocker arm 55. The rocker arm 55 is mounted upon a fixed pivot 56 with its other end in pin and slot engagement with a crank 57 carried by the reversing shaft 12a. The reversing shaft 12a is provided also with a positioning cam 58 engageable with a spring pressed detent 59, thereby selectively to maintain the reversing shaft in either its forward or its rewind position. The pins 48 and 49 are thus in one end of the slots 50 and 51 for forward operation and in the opposite ends for reverse operation. In both positions the damping links are normally angularly disposed with respect to the perpendicular from the common diameter of the associated driving and disks.

The driving ratio of the transmission elements 24 and 25 is varied by movement of the control links 42 and 40, respectively, in response to movement of the dancer pulleys 7 and 8, respectively. For this purpose, the dancer pulleys 7 and 8 are mounted respectively upon arms 60 and 61 extending laterally from a pair of rotatable shafts 62 and 63, respectively. The shafts 62 and 63 are mounted in suitable bearings (not shown) and are biased by helical springs 64 and 65, respectively, to maintain tension on the wire 1. Specifically, the shaft 62 is biased in a counterclockwise direction and the shaft 63 is biased in a clockwise direction, as viewed at Fig. 1. The pulley arms 60 and 61 may, if desired, be made of relatively stiff spring material to absorb shock and thereby add to the stability of the transmission mechanism. The shafts 62 and 63 are each provided at one end with collars 66 and 67, respectively, to which the biasing springs 64 and 65 are connected. A pair of links 68 and 69 are eccentrically pivoted to the collars 66 and 67, respectively, at one end and have their other ends pivotally connected to the rocker levers 45 and 44, respectively, at the ends opposite the control links 42 and 40, respectively.

The idler pulleys 9 and 10 are rotatably mounted upon axially movable and non-rotatable shafts 70 and 71, respectively, disposed parallel to the shaft 18. The shafts 70 and 71 are continuously reciprocated by a level winding mechanism 72 driven from the shaft 22 by a worm 73 mounted thereon. The worm 73 meshes with a worm wheel 74 mounted upon a counter shaft 75 the other end of which carries a spur gear 76. The spur gear 76 meshes with a spur gear 77 mounted upon a counter shaft 78 the other end of which carries a bevel gear 79. The bevel gear 79 cooperates with a bevel gear 80 mounted upon a shaft 81 perpendicular to the shaft 18 and carrying at its opposite end a pair of eccentric cam disks 82 and 83. The disks 82 and 83 peripherally engage a pair of level winding levers 84 and 85, respectively, which are mounted upon fixed pivots 86 and 87, respectively. The movable ends of the levers 84 and 85 engage axial slots in the shafts 70 and 71, respectively, and the levers are biased into engagement with the periphery of the disks 82 and 83, respectively, by helical compression springs 88 and 89 engaging collars 90 and 91 on the shafts 70 and 71, respectively. It will be evident that as the levers 84 and 85 are oscillated by the cam disks their respective shafts are continuously reciprocated to effect level winding of the wire 1 upon the reels 2 and 3.

It has been found that because of friction losses in the dancer pulleys 7 and 8 and in the recording and erasing heads 4 and 5, respectively,

the tension on opposite sides of the capstan 6 may be maintained equal only if the spring tension on the forward dancer pulley is somewhat greater than that on the trailing dancer. By the forward dancer pulley is meant that dancer associated with the take-up reel. For this purpose, the biasing force exerted by the spring 64 upon the dancer pulley 7 is adjusted to be greater than that exerted by the spring 65 upon the dancer pulley 8, and an additional spring 92 controlled by the reversing shaft 12a is arranged to add to the effect of the spring 65 in forward operation when the reel 3 is serving as a take-up reel and to exert little or no effect upon the spring 65 when the reel 2 is serving as a take-up reel in rewind operation. For this purpose, the spring 92 is connected at one end to the lower end of the link 69 and at the other end to an arm 93 mounted upon the reversing shaft 12a. The arm 93 is so disposed that, when the reversing shaft is in its forward position, tension is applied to the spring 92, while when the reversing shaft is in its rewind position the spring 92 is substantially untensioned. By this arrangement, it is possible to maintain the tension on opposite sides of the capstan pulley 6 substantially equal, so that there is no tendency for the wire to slip upon the capstan.

With the foregoing understanding of the construction and arrangement of a wire recording apparatus embodying my invention, the mode of operation of the apparatus will be fully understood from the following description.

Let it first be assumed that the reversing lever 12 is positioned for forward operation, as shown at Fig. 1, so that the wire 1 is supplied from the reel 2 to the reel 3, passing through first the erasing head 5 and then the recording head 4. In this operation, the friction disk 17 is driven by the motor 13 in a counterclockwise direction, as indicated upon the drawing. Also, the damping links 41 and 43 are disposed with their lower ends in the right-hand ends of the slots 50 and 51, respectively. In this position, the pins 48 and 49 are displaced to the right of a perpendicular to the common diameter of the driving and driven disks. The control links 40 and 42, in the normal mid-position of the apparatus shown, are substantially vertical or perpendicular to the common diameter.

In the counterclockwise or forward direction of rotation of the disk 17, the belt 20 and pulley 21 rotate the disk 23 in a counterclockwise direction. The capstan pulley 6, being connected directly to the shaft 18, also rotates counterclockwise and in the same direction as the disk 23. The variable transmission 24 connecting the disk 23 to the disk 26 effects clockwise rotation of the disk 26 and the connected reel 2. Similarly, the variable transmission 25 connecting the disk 23 to the disk 27 effects clockwise rotation of the disk 27 and connected reel 3. Both reels are thus positively connected to be driven in the direction of wire travel. In the forward direction of operation, the reel 2 serves as a supply reel and the reel 3 functions as a take-up reel. As the wire travels from one reel to the other, the level winding mechanism 72 continuously reciprocates the shafts 70 and 71 and the connected idler pulleys 9 and 10, respectively, thereby smoothly to wind the wire upon the take-up reel.

It is, of course, desirable to maintain the wire tension equal on both sides of the capstan 6, so that there is no tendency for the wire to slip on the capstan. If the wire has the same desired

tension on both sides of the capstan, and if the reels contain about equal lengths of wire wound thereon, the dancer pulleys 7 and 8 will be maintained in such positions that the jackshafts 30 and 31 of the variable transmission mechanisms 24 and 25 lie along the common diameters of their associated driving and driven disks. The disks 26 and 27 are then driven at the same speed as that of the driving disk 23. It is this position of the mechanism which has been illustrated at Fig. 1 and to which the term "normal position" in the claims refers. It will be recalled also that, in order that the wire tension upon opposite sides of the capstan 6 may be maintained equal, the biasing force on the dancer pulley 8 is greater than that on the dancer 7 in forward operation and less than that on the dancer 7 in reverse operation. As shown on the drawing, the spring 92 connected to the reversing lever shaft is positioned to aid the helical spring 65 in biasing the dancer pulley 8 for clockwise rotation.

It will of course be understood that the symmetrical positions of the variable transmission mechanisms 24 and 25 illustrated on the drawing cannot be maintained except for a short interval during the operation when the diameter of the wire upon both reels 2 and 3 is approximately the same. In operation, the capstan 6 drives the wire 1 at a predetermined constant linear speed, while the transmission mechanisms 24 and 25 control the speeds of the reels 2 and 3, respectively, to maintain the wire tension constant adjacent the reels as the amount of wire on the reels changes. Thus as the wire winds up on the take-up reel its speed is gradually reduced, while the speed of the supply reel is gradually increased.

Let it be assumed, for example, that the diameter of the coil of wire upon the reel 2 is such that wire is supplied too rapidly from the reel 2 and the tension at the dancer pulley 7 becomes less than a predetermined desired value. In such a case, the dancer pulley 7 moves a small distance in a counterclockwise direction under the action of its biasing spring 64, and the consequent rotation of the crank hub 66 moves the link 68 downwardly. Thus through the rocker arm 45 the control link 42 of the variable transmission 24 is moved upward and the quill 32 of this transmission element is rotated about its point of pivotal connection with the damping link 43. Since the jackshaft 30 is now no longer diametrically disposed with respect to disks 23 and 26, it has imparted thereto an axial component of movement. With the friction roller 35 above the horizontal diameter of the disk 26, this axial movement is toward the right as shown in the drawings, or away from the disk 26 and toward the disk 23. As the jackshaft 30 moves axially, the damping link 43 rotates in a clockwise direction about its lower end thereby to raise the friction roller 34 of the transmission 24 and to restore the quill 32 to a horizontal position. Eventually, a new position of equilibrium is reached in which the jackshaft 30 lies parallel to and above the common diameter of the disks 23 and 26 with the friction roller 35 spaced from the center of the disk 26 by a distance greater than that between the friction roller 34 and the center of the disk 23. It is therefore evident that the speed of the disk 26 will be less than that of the disk 23, and that the speed of the reel 2 is thus reduced, thereby to prevent further decrease in the tension of the wire 1 as it leaves the reel and to maintain the tension substantially constant within differential limits.

Similarly, it will be evident that, if the reel 2 is revolving too slowly, so that the tension at the dancer pulley 7 increases, the dancer pulley is moved in a clockwise direction, the link 48 is raised, and the control link 42 is lowered. With the friction roller 35 below the horizontal center line of the disk 26, axial movement of the jackshaft 30 takes place to the left, as shown in the drawing, or away from the disk 23. When the quill 32 moves in this direction, the damping link 43 rotates about its lower end in a counter-clockwise direction thereby to lower the right end of the shaft 30 below the common diameter of the disks 23 and 26. Ultimately, a new position of equilibrium is reached with the jackshaft 30 parallel to and below the common diameter of the disks and the distance between the roller 35 and the center of the disk 26 less than that between the roller 34 and the center of the disk 23. Thus, the disk 26 is driven at a speed greater than that of the disk 23, so that wire is supplied from the reel 2 at a greater rate, thereby to maintain the desired tension within differential limits.

The variable transmission mechanism 25 functions in an entirely similar manner to control the speed of the take-up reel 3 in such a way that the tension of the wire between the capstan 6 and the reel 3 is maintained at the desired value. In general, therefore, it will be evident that, at the beginning of a winding operation, when substantially all the wire is on the supply reel 2 and very little wire upon the reel 3, the reel 2 is driven more slowly than the driving disk 23 and the reel 3 driven more rapidly than the driving disk 23. As the roll of wire is reduced upon the reel 2, the speed of the reel 2 gradually increases, and as the wire builds up upon the reel 3, the speed of the reel 3 gradually decreases. Throughout the operation, the linear speed of the wire 4 is maintained constant by the wire driving capstan 6.

Attention is directed to the fact that the damping links 41 and 43 are differently disposed in the two transmission mechanisms 24 and 25, and that their relative disposition is reversed upon reversal of the wire movement. This disposition is required by the directions of axial movement required of the jackshafts 30 and 31 in the two transmission mechanisms. In general, it is to be noted that the damping links 41 and 43 are so inclined that axial movement of the associated jackshaft in response to movement of the associated control link is in such a direction that the damping link tends to restore the quill 32 to a horizontal position as a result of the axial movement. For such restoring action the damping links must always be disposed at such an angle to the connected jackshaft that, when the jackshaft is tilted toward the perpendicular to the damping link, axial movement of the shaft will take place in the direction away from the damping link. Specifically, in the embodiment of the invention shown and with the direction of rotation of the parts assumed for forward operation, it will be noted that the links 42 and 43 are spaced apart farther at their lower ends than at their upper ends, while the links 40 and 41 are spaced closer at their lower ends than at their upper ends. The spacing of the upper ends of course is fixed by pivotal connection to the quill 32. These relations will be clarified by reference to Fig. 3, in which I have shown a line diagram of the linkage shown at Fig. 1. At Fig. 3, I have shown by dotted lines tilted positions of the jackshafts 30 illustrating the above relation for for-

ward wire movement. It will be evident that the same relation exists for reverse wire movement only if the damping links are shifted to the opposite ends of the slots in the plate 53.

In order further to explain the theoretical relations affecting the operation of my apparatus, I have shown at Fig. 4 a line diagram of a simplified friction transmission similar to the transmissions 24 and 25 described above, but in which the damping function is omitted. In the arrangement shown at Fig. 4 the jackshaft 30 is pivotally mounted at a fixed point 100 and is axially movable with respect to its pivot point. The shaft is shown in a tilted position. The driving disk 23 and the driven disk 27 are shown with their directions of rotation as previously assumed. The disks 23 and 27 are in contact with the rollers 34 and 35, respectively. The velocity of the disk 23 at its point of contact with the roller 34 is illustrated by the vector V_{23} , and the velocity of the disk 27 at its point of contact with the roller 35 is illustrated by the vector V_{27} . The disk 23 therefore tends to impart to the roller 34 a tangential velocity V_{34T} and an axial velocity V_{34A} , while the disk 27 tends to impart to the roller 35 a tangential velocity V_{35T} and an axial velocity V_{35A} . It will thus be evident that, since the jackshaft 30 is axially movable, the shaft and its connected rollers will move axially in the direction indicated toward the center of the disk 23 and away from the center of the disk 27. Thus, in the course of one revolution, the point of contact of the roller 34 with the disk 23 will follow a spiral path 101 indicated by dotted line at Fig. 4. It may be demonstrated mathematically that the theoretical axial velocities V_{34A} and V_{35A} are not the same, so that there will necessarily be some slight slippage.

From Fig. 4, it will be evident that if desired the jackshaft 30 may be slidably mounted in a short quill centrally pivoted at a fixed point, rather than being carried on the control and damping links described with reference to Figs. 1 and 3. At Fig. 5, I have shown a fragmentary line diagram of a portion of the apparatus including one such quill 102 centrally pivoted at a fixed point and provided with an extending arm 102a. Those portions of the apparatus shown at Fig. 5 corresponding to like elements shown in the other figures have been assigned the same reference numerals. The mechanism of Fig. 5 is inverted with respect to Fig. 1 and the wire is oppositely wound on the reels. This relation should be borne in mind in noting the correspondence of elements between the two figures. It will be noted at Fig. 5 that the quill 102 is shorter than the jackshaft 30 and that the jackshaft 30 is axially movable within the quill. The dancer pulley 7 of Fig. 5 is mounted upon a bell crank 103 which is pivotally mounted at a fixed point 104 and connected to the jackshaft arm 102a by a link 105. The dancer pulley is biased by means of a spring 106 in a direction to apply tension to the wire 4. The jackshaft 30 is shown tilted at an angle α with respect to the common diagonal through the disks 23 and 26 and displaced a distance x from its mid-position in the quill 102. It will be understood that the tilting of the jackshaft at the angle α results from lifting of the dancer pulley 7 through a distance y from its position when the jackshaft is horizontal, and that the axial movement of the jackshaft through the distance x arises from its tilting as explained with respect to Fig. 4.

It may be demonstrated by the equations of

motion that, for the mechanism shown at Fig. 5, the axial velocity of the jackshaft 30 is a function of the distance y only, and that, because of the speed changes in the disks effected by the axial movement, simple harmonic axial oscillation of the jackshaft will result. In order to effect damping of such oscillations, it is necessary to introduce into the axial velocity of the jackshaft a function of the displacement x . This is accomplished by the damping links 41 and 43 previously described. As will now be evident, these damping links have the effect of reducing the angle α and thereby reducing the axial velocity of the jackshaft as the displacement x increases and without affecting the displacement y . It will be evident that other suitable damping mechanisms may be utilized to accomplish this purpose within the scope of my invention.

At Fig. 6, I have shown a further embodiment of my invention having a control and damping linkage similar to that of Fig. 1 and including additionally mechanisms for braking the reel when the wire is slack, such as in the event of wire breakage or when the wire is changed. Those elements of Fig. 6 corresponding to like elements of Fig. 1 have been assigned the same reference numerals. In noting the correspondence of parts in the two figures, it should be observed that the pulley orientation of Fig. 6 is reversed with respect to Fig. 1 and the wire is oppositely wound on the reel. At Fig. 6, the dancer pulleys 7 and 8 are mounted upon pivoted arms 60 and 61 and biased by springs 64 and 65, respectively, as at Fig. 1 and links 68 and 69 connect the arms 60 and 61 with the leaves 45 and 49, respectively. At Fig. 6, however, I provide also a pair of brake shoes 107 and 108 pivotally mounted upon fixed pivots 109 and 110 and arranged to engage the driven disks 27 and 26, respectively. If desired, of course, the brake shoes may engage the reels directly or may engage separate brake drums on the reel shaft. The brake shoes are actuated by links 111 and 112 connecting the shoes to extensions on the dancer pulley levers 61 and 60, respectively. Thus if the wire breaks or becomes slack for any reason, the brakes will come into action. Preferably, the brakes have a differential action, so that more braking is obtained upon any reel when it is turning in a direction to unwind the wire. Thus, the supply or trailing reel is braked the most so that the wire is kept taut. The brakes will ordinarily come into action only when the wire is changed and if the initial position of the rollers is incorrect for the diameters of the new reels. The brake on the delivery reel will then check the rotation of the reel during the first two or three turns until equilibrium is established.

While I have described only certain preferred embodiments of my invention by way of illustration, many modifications will occur to those skilled in the art and therefore, it is intended that the invention should not be limited except as defined by the following claims.

What I claim as new and desire to secure by Letters Patent of the United States is:

1. In a tension control system for a traveling strip of material, a pair of spaced reels, constant speed driving means engaging said strip intermediate said reels, a driving disk, a driven disk connected to each said reel and positioned in the plane of said driving disk, a pair of axially movable jackshafts each carrying at one end a friction roller engaging said driving disk and

5

at the other end a friction roller engaging one of said driven disks, and separate means responsive to the tension of said strip between each said reel and said strip driving means for tilting the associated jackshaft with respect to the common diameter of said disks.

10

2. In a tension control system for a traveling strip of material, a pair of spaced reels, constant speed driving means engaging said strip intermediate said reels, a driving disk, a driven disk connected to each said reel and positioned in the plane of said driving disk, a pair of axially movable jackshafts each carrying at one end a friction roller engaging said driving disk and at the other end a friction roller engaging one of said driven disks, separate means responsive to the tension of said strip between each said reel and said strip driving means for tilting the associated jackshaft with respect to the common diameter of its driving and driven disks thereby to effect axial movement of said jackshaft, and separate means responsive to axial movement of said jackshafts for restoring the associated jackshaft to a position substantially parallel to said common diameter.

15

3. In a tension control system for a traveling strip of material, a pair of spaced reels, constant speed driving means engaging said strip intermediate said reels, a driving disk, a driven disk connected to each said reel and positioned in the plane of said driving disk, a pair of axially movable friction spools each engaging said driving disk and one of said driven disks and being normally disposed with their axes substantially parallel to the common diameter of the associated driving and driven disks, separate means responsive to the tension of said strip between each said reel and said strip driving means for tilting the associated friction spool with respect to said common diameter thereby to effect axial movement of said spools and change the driving ratio of said disks, and separate means responsive to axial movement of said spools for controlling the angle of tilt of the associated spool to prevent hunting thereof.

20

4. In a tension control system for a traveling strip of material, a pair of spaced reels, means engaging said strip intermediate said reels for driving said strip at a predetermined linear speed, a driving disk, a driven disk connected to each said reel and positioned in the plane of said driving disk, a pair of jackshafts each carrying at one end a roller engaging said driving disk and at the other end a roller engaging one of said driven disks, a pair of parallel pivoted links each supporting one end of one of said jackshafts in a normal position substantially parallel to the common diameter of the associated driving and driven disks, and separate means controlled by the tension of said strip between each said reel and said strip driving means for tilting the associated jackshaft about said supporting link thereby to effect axial movement of the shaft, said supporting links being normally angularly disposed with respect to said common diameters thereby to effect restoring movement of said jackshafts toward said normal position in response to axial movement thereof.

5. In a tension control system for a traveling strip of material, a pair of spaced reels, constant speed driving means engaging said material intermediate said reels, a driving disk, a driven disk connected to each said reel and positioned in the plane of said driving disk, a pair of jackshafts each carrying at one end a friction roller en-

75

gaging said driving disk and at the opposite end a friction roller engaging one of said driven disks, a pair of quills in which said jackshafts are mounted, a pair of pivoted links supporting each said quill in a normal position parallel to the common diameter of the associated driving and driven disks, and means including one link of each said pair of links and responsive to the tension of said strip between each said reel and said strip driving means for tilting the associated quill with respect to said common diameter thereby to effect axial movement of the associated jackshaft, the other link of each said pair of links being disposed to restore the connected quill to parallel relation with said common diameter in response to said axial movement.

6. A constant tension control system for a traveling strip of material comprising a reel, a driven disk connected to said reel, a driving disk in the plane of said driven disk, a jackshaft carrying at one end a friction roller engaging said driven disk and at the other end a friction roller engaging said driving disk, means normally supporting said jackshaft in substantially parallel relation with the common diameter of said disks, and means responsive to the tension of said strip for tilting said jackshaft with respect to said common diameter thereby to effect axial movement of said jackshaft and to change the driving ratio between said disks.

7. A constant tension control system for a traveling strip of material comprising a reel, a driven disk connected to said reel, a driving disk in the plane of said driven disk, a friction spool, means normally supporting said spool in substantially parallel relation with the common diameter of said disks with opposite ends of said spool engaging said driving and driven disks respectively, means responsive to the tension of said strip for tilting said spool with respect to said common diameter thereby to effect axial movement of said spool and to change the driving ratio between said disks, and damping means comprising means responsive to said axial movement for restoring said spool to its normal parallel relation with respect to said common diameter.

8. A constant tension control system for a traveling strip of material comprising a reel, a driven disk connected to said reel, a driving disk in the plane of said driven disk, a friction spool having opposite ends engaging said driving and driven disks respectively, means including a pivoted link normally having an angular relation with respect to the common diameter of said disk for supporting said spool in a normal position with its axis substantially parallel to said common diameter, means responsive to the tension of said strip for tilting the axis of said spool about said link thereby to effect axial movement of said spool, said link restoring the parallel relation between the axis of said spool and said common diameter in response to said axial movement.

9. A constant tension system for a traveling strip of material comprising a reel, a driven disk connected to said reel, a driving disk in the plane of said driven disk, a jackshaft carrying at one end a friction roller engaging said driven disk and at the other end a friction roller engaging said driving disk, a quill in which said jackshaft is mounted, a pair of links pivotally connected to opposite ends of said quill and pivotally mounted to support said quill in a normal position parallel to the common diameter of said disks, said

links being angularly disposed with respect to each other and one of said links being normally substantially perpendicular to said common diameter, and means including said perpendicular link and responsive to the tension of said strip for tilting said quill about the other of said links thereby to effect axial movement of said jackshaft.

10. A constant tension control system for a traveling strip of material comprising a reel, a driven disk connected to said reel, a driving disk in the plane of said driven disk, a jackshaft carrying at one end a friction roller engaging said driven disk and at the other end a friction roller engaging said driving disk, a quill in which said jackshaft is mounted, a pair of supporting links pivotally connected to opposite ends of said quill and pivotally mounted to support said quill in a normal position substantially parallel to the common diameter of said disks, said links being angularly disposed with respect to each other and one of said links being normally substantially perpendicular to said common diameter, means including said perpendicular link and responsive to the tension of said strip for tilting said jackshaft about the other of said links thereby to effect axial movement of said jackshaft and to change the driving ratio between said disks, means for reversing the direction of rotation of said driving disk, and means associated with said reversing means for reversing the angular relation of said links, said angularly disposed links being arranged in either direction of rotation of said disks to restore the parallel relation between said jackshaft and said common diameter in response to axial movement of said jackshaft.

11. A constant tension control system for a traveling strip of material comprising a reel, a driven disk connected to said reel, a driving disk in the plane of said driven disk, means associated with said driving disk and engaging said strip for driving said strip at a predetermined linear speed, a jackshaft carrying at one end a friction roller engaging said driven disk and at the other end a friction roller engaging said driving disk, means normally supporting said jackshaft in substantially parallel relation with the common diameter of said disks, and means responsive to the tension of said strip for tilting said jackshaft with respect to said common diameter thereby to effect axial movement of said jackshaft and to change the driving ratio between said disks.

12. In a tension control system for a traveling strip of material, a pair of spaced reels, means intermediate said reels for driving said strip at a predetermined linear speed, means for driving both said reels in the direction of travel of said strip, separate means responsive to the tension of said strip between each said reel and said strip driving means for controlling the speed of the associated reel, and means actuated by said tension responsive means for braking said reels upon a predetermined decrease in the tension of said strip.

13. In a tension control system for a traveling strip of material, a pair of spaced reels, means intermediate said reels for driving said strip at a predetermined linear speed, means for driving both said reels in the direction of travel of said strip, separate means responsive to the tension of said strip between each said reel and said strip driving means for controlling the speed of the associated reel, differential braking means associated with each said reel and arranged to apply to each reel a braking force greater in the direc-

tion of unwinding of said strip than in the direction of winding, and means responsive to a predetermined decrease in the tension of said strip for actuating said braking means.

14. A reeling apparatus comprising a pair of spaced reels carrying an elongated strip of material, a driving capstan engaging said strip intermediate said reels, operating means slidably engaging said strip adjacent said capstan, a pair of dancer pulleys engaging said strip and positioned to include said capstan and said operating means therebetween, means for applying to said dancer pulleys fixed biasing forces of unequal value, means for reversing said capstan, and means controlled by said reversing means for superposing an additional bias upon the dancer pulley having the smallest fixed bias.

15. A reeling apparatus comprising a pair of spaced reels carrying an elongated strip of material, a driving capstan engaging said strip intermediate said reels, operating means slidably engaging said strip adjacent said capstan, a pair of dancer pulleys engaging said strip and positioned to include said capstan and said operating means therebetween, spring means for applying to said dancer pulleys fixed biasing forces of unequal value, means for reversing said capstan, and additional spring means controlled by said reversing means for increasing the bias of the dancer pulley having the smallest fixed bias to a value greater than the larger fixed bias by approximately the difference between said fixed biasing forces.

16. A reeling apparatus comprising a pair of spaced reels carrying an elongated strip of material, a driving capstan engaging said strip intermediate said reels, means for driving either of said reels as a take-up reel, operating means slidably engaging said strip adjacent said capstan, a pair of dancer pulleys engaging said strip and positioned to include said capstan and said operating means therebetween, spring means for applying to said dancer pulleys fixed biasing forces of unequal value, means for reversing said capstan, and additional spring means controlled by said reversing means for increasing the bias of the dancer pulley having the smallest fixed bias by approximately twice the difference between said fixed biasing forces, said reversing

means being arranged always to maintain the larger bias upon the forward dancer pulley adjacent the take-up reel.

17. A magnetic recording and reproducing apparatus comprising a pair of spaced reels carrying an elongated magnetic record medium, a driving capstan engaging said record medium intermediate said reels, means for driving either of said reels as a take-up reel, a magnetic operating head frictionally engaging said record medium adjacent said capstan, a pair of dancer pulleys engaging said record medium and positioned to include said capstan and said operating head therebetween, spring means for applying to said dancer pulleys fixed biasing forces of unequal value, additional spring means having a disabled position and a position for superposing upon the smaller of said biasing forces an additional bias equal approximately to twice the difference between said fixed biasing forces, means for reversing said capstan, and means controlled by said reversing means for positioning said additional spring means always to maintain the larger net bias upon the dancer pulley adjacent the take-up reel.

ARTHUR W. SEAR.
